(57) CLAIM

The ornamental design for a brim and trim accessories for cap or visor, as shown and described.

DESCRIPTION

FIG. 1 is a top exploded view of a brim and trim accessories for cap or visor showing my new design;

FIG. 2 is a bottom exploded view thereof;

FIG. 3 is a side view, taken from the left side of FIG. 1;

FIG. 4 is a side view, taken from the right side of FIG. 1;

FIG. 5 is a rear view of FIG. 1;

FIG. 6 is a front view of FIG. 1; and,

FIG. 7 is a perspective view in assembly condition.

The broken line showing a visor band is for illustrative purposes only and forms no part of the claimed design.
